POLE SUPPORTED SHELVING UNIT

Richard Sylvan, Chicago, Ill., assignor to Queen Manufacturing Co., Inc., Chicago, Ill., a corporation of Illinois

Filed June 26, 1963, Ser. No. 75,533

Term of patent 14 years

(Cl. D80—10)

FIG. 2.

FIG. 3.

FIGURE 1 is a perspective view of my design for a pole supported shelving unit;

FIGURE 2 is a top view of a shelf incorporating my design; and

FIGURE 3 is a side view of a shelf incorporating my design.

The dominant features of my design reside in the portions shown in full lines, it being understood that the partially shown dotted grill work or grid support area is continuous throughout the plane area of the shelves shown in FIGURE 1 and FIGURE 2.

I claim:

The ornamental design for a pole supported shelving unit, as shown and described.
